SCALPING APPARATUS

Louis Burmeister, Milwaukee, Wis.

Application March 28, 1934, Serial No. 717,777

4 Claims. (Cl. 269—326)

This invention relates to improvements in the scalping apparatus.

In the milling of wheat, the raw material or wheat kernel is first tempered by treatment with water or the like and then run thru a series of breaking, separating, and sizing steps to produce the final product, which is wheat flour. A certain amount of so-called ash is present in all wheat kernels, and while a limited percentage of ash is desirable in flour, any amount over a certain maximum is detrimental; as it affects the color and quality of the product.

Heretofore, it has been common practice to first run the wheat kernels thru disintegrating or reducing rolls and then deliver the crushed material to bolting devices. These bolting devices may consist of a plurality of superimposed spiral sieves for gradually separating the crushed fragments into bran, sizings, and flour. To bring about progressive movement of the material in this type of bolting device, the latter is gyrated or caused to rotate in a horizontal plane. The first step which takes place in the ordinary bolter is the scalping operation, which is accomplished with relatively coarse sieves. Due to the type of movement, i. e. horizontal movement, imparted to the bolter, there is necessarily a large amount of friction between the sieves and the crushed material; so that an undesirable grinding action takes place. This grinding action causes powdering of the particles of wheat kernels, which cause ash, and therefore permits a relatively large percentage of powdered ash to pass thru all the sieves and enter into the final product. If this powdering action did not take place, a large percentage of the ash would remain in coarse form and be discharged without forming part of the flour.

It is one of the objects of the present invention to provide an improved method of milling wherein the scalping operation is performed independently of the bolter in a manner which minimizes the amount of powdering action and therefore limits the amount of ash in the flour.

A more specific object of the invention is to provide a method as above described wherein the scalping step is performed in advance of the bolter by imparting a vertical bouncing movement to the crushed fragments instead of a horizontal grinding movement.

A further object of the invention is to provide an improved apparatus for effecting commercial exploitation of the above method.

A more specific object of the invention is to provide a scalping apparatus including a sieve box wherein the latter is provided with a novel

type of floating mounting and wherein novel means is provided for imparting vibratory movement to the sieve box, said vibratory movement being in a vertical plane.

A further object of the invention is to provide in apparatus as above described, means for effecting adjustment of the angle of the sieve box and means for adjustably varying the path of vibratory movement.

A further object of the invention is to provide in a scalping apparatus or the like novel means cooperable with the sieves to prevent blinding, that is, the wedging of particles within the mesh of the sieve.

A further object of the invention is to provide an improved method for the purpose described which materially improves the quality and whiteness of the flour and which is otherwise well adapted to accomplish the objects sought.

With the above and other objects in view, the invention consists of the improved art of milling and all the parts and combinations thereof as set forth in the claims and all equivalents thereof.

In the accompanying drawings, illustrating one complete embodiment of the preferred form of the invention, in which the same reference numerals designate the same parts in all of the views:

Fig. 1 is a side elevational view of the improved apparatus, parts being broken away;

Fig. 2 is a horizontal sectional view thru the upper portion of the frame, showing the sieve box in plan view;

Fig. 3 is a cross-sectional view taken on line 3—3 of Fig. 1;

Fig. 4 is a fragmentary sectional view taken on line 4—4 of Fig. 1;

Fig. 5 is a vertical sectional view taken thru one end of the driving shaft and eccentric weight mechanism, parts being broken away;

Fig. 6 is an enlarged fragmentary sectional view illustrating the support for and adjustment of the coil springs in connection with the sieve box mounting;

Fig. 7 is a diagrammatic side elevational view, showing one end of the sieve box and the type of vibratory movement imparted thereto; and

Fig. 8 is a diagrammatic view showing the various steps in the improved method of milling.

Referring more particularly to the drawings, a suitable open frame is provided for supporting the sieve box 8; and said frame consists of vertical angle bars 9 and 10 on each side, connected by upper and lower horizontal angle members 11 and 12.

Secured to each side between the vertical angle bars

bars 9 by means of bolts 13 is a plate 14. Each plate is formed with a central aperture and with four perforations for the reception of bolts 15, which serve to secure a spring positioning member or plate 16 in position. The latter member is cast with an outwardly extending, circular flange 17 and with a central opening 18 of less diameter than the flange. Adjacent the inner side of the flange, are four pairs of spaced brackets 19. Between each pair of brackets is positioned a cupped spring washer 20, substantially T-shaped in cross-section, engaged by bolts 20' for adjustably moving the cupped spring washers (see Fig. 6).

Secured to the lower side of the sieve box at each end thereof by means of clamps 21, are supporting shafts 22 and 23. Each of said shafts projects beyond the sides of the sieve box and has its ends formed with squared hub members 24 having four studs 25 projecting therefrom. Coil springs 26 are positioned within the plate 16 with their ends engaged between the studs 25 and the reduced inner portions of the cupped spring washers 20. The plates 16 at the lower end of the sieve box are identical in construction to the plates at the other end and heretofore described in detail. These plates are also mounted on larger plates 27 similar to the plates 14. The plates 27, however, are each formed with four slotted openings 28 thru which the bolts 29 extend which secure the plate 16 in position. Thus, the plate 16 may be adjusted laterally with respect to the plate 27.

Instead of being secured directly to the vertical angle bars 10, the plates 27 have offset clamping strips 30 secured to their rear side edges by bolts 31; so that the plate 27 may be clamped in any desired vertical position on the angle strips 10, as shown in Fig. 2. By loosening the bolts 31, the position may be readily changed, altho the bolts 29 must also be loosened to permit movement of the latter with respect to the slots 28.

In order to further hold the plate 27 in a desired position of adjustment, an adjustment screw 32 is employed which connects a lower angle strip 33 of the plate 27 with an angle strip 34 positioned across the space between the angle bars 10. Nuts 35 and 35' are utilized to lock the adjustment member 32 in a desired position.

From the above, it may be seen that the sieve box is mounted on the shafts or supporting axles 22 and 23 with the latter having a yielding bearing at each end. Thus, the sieve box is mounted so as to be yieldingly floating.

Journalled in bearings 36 beneath the central portion of the sieve box is a shaft 37 (see Figs. 1 and 3), said shaft having a pulley 38 mounted rigidly thereon for connection with a driving source to rotate the shaft 37. Each end of the shaft 37 has keyed thereto a hub member 39 carrying a fixed weight member 40. Threaded in the weight member 40 are rods 41, and slidably mounted on said rods against the tension of coil springs 42, is a movable weight member 43. A central guiding rod 44 has one end secured to a transverse bar 45 and has its other end threaded in the hub 39, the weight being movable on said rod. A collar 46 may be provided on the rod to be held in any desired position by means of a set screw 47 to limit the outward movement of the weight 43.

The above construction is such that when the shaft 37 is rotated, the weight 43 on each end will move outwardly against the tension of the coil springs 42 due to centrifugal force to provide a

rotating eccentric weight structure which will cause the sieve box to vibrate in a vertical plane. Due to the sliding mounting of the weight and the coil spring structure, it will be seen that the outward position of the weight will vary in accordance with the speed of rotation, that is, the faster the shaft is rotating, the more pressure there will be on the springs and the farther outwardly the weight will be permitted to move. This results in a smooth, balanced vibration.

It is preferred to have the vertically extending coil springs 26 in connection with the sieve box mounting of greater strength than the horizontally extending springs, so that when the sieve box is being vibrated due to the action of the eccentric weight, the hub portions 24 of the sieve box supporting shafts will move thru a substantially oval course in a vertical plane, as indicated by the arrows in Fig. 7. This exact action may be varied to meet requirements by manipulation of the adjustment bolts 20'.

The sieve box is formed with a plurality of sieves 48 and 49, and each sieve may be supported at its side edges as at 50 and 51 and also by central longitudinal strips 52 and 53 (see Figs. 1 and 3).

Mounted on the strips 52 and 53 above the screening, are a plurality of blocks 54, each block having one end of a flexible metallic strip 55 secured thereto, as at 56. The other end of the strip has secured thereto an impact member 57, preferably in the form of a hard rubber ball. A coil spring 58 is positioned beneath an intermediate portion of the strip 55 on a guiding bolt 59. The construction is such that when the sieve box is vibrated, the flexible strips 55 will vibrate against the tension of the coil springs 58, causing the impact members 57 to strike the screening and thereby dislodge particles which may become jammed in the mesh.

The raw material may be inserted into an inlet opening 60 which directs it onto the upper screen. The upper screen may terminate short of the end of the sieve box, as at 61, to deposit material on the end of the lower screen 49; and with such an arrangement, there may be a common discharge 45. 62 for the two screens. It may, however, be desirable to have the upper screen 48 of full length and provided with a separate discharge spout.

Material which passes thru both the screens, falls on the bottom of the sieve box and is discharged from a lower spout 63.

In the usual process of milling, the raw material, after being tempered by treatment with water or the like, is run thru disintegrating or reducing rolls 64 (see Fig. 8) and then directly into a bolter 65. As before explained, the usual bolter consists of a plurality of superimposed spiral sieves for gradually separating the crushed fragments into bran, sizing, and flour; and the bolter is gyrated or caused to rotate in a horizontal plane. The 60 first screens in the usual bolter perform a scalping operation, and due to the type of movement, i. e. horizontal movement, imparted to the bolter, there is a large amount of friction between the sieves and the crushed material; so that non-desirable grinding action takes place. This grinding action causes powdering of the particles of wheat kernels, which cause ash, and therefore permits a relatively large percentage of the powdered ash to pass thru all of the sieves and 70 enter into the final product.

With applicant's improved method, the scalping screens or sieves of the bolter are eliminated; and applicant's improved apparatus, designated generally by the numeral 66 in Fig. 8, is inserted 75

between the reducing rolls 64 and the bolter 65. Due to the novel type of movement imparted to the sieve box in the unit 66, illustrated in Fig. 7 and before referred to, a bouncing action will take 5 place on the sieves, as indicated by the arrows in said figure, so that all of the particles will jump above the plane of the sieves and then back onto the sieves, with the finer particles being thereby shaken thru. Thus, the scalping is performed 10 without the usual friction resulting from the scalping operation in the bolter wherein the material is merely caused to rotate horizontally while in contact with the screening. As a result, the amount of ash which passes thru both of the 15 screens of the unit 66 and into the bolter from the discharge spout 63 is reduced to a minimum. The material is then acted upon by the bolter with the scalping portion of the bolter eliminated, so that the bolter does all of the other usual operations. The coarser material which does not pass 20 thru both of the screens of applicant's unit 66 may be directed back to a second set of reducing rolls, as indicated by the arrows 67 in Fig. 8, and re-crushed. It may be then directed into a second 25 scalping apparatus 66' for further operation.

Thus, it will be seen that applicant has provided a substantial change in procedure by substituting a particular type of vibratory action in performing the scalping operation and that this operation 30 is performed independently of the bolter and prior to passage of material therethru.

Experiments have proven that this method of procedure is greatly superior to the methods of procedure now in use and that the amount of ash in the final product is maintained at a desirable percentage, so that the flour is of unusual 35 whiteness and of superior quality.

Altho only one form of the invention has been shown and described, it is obvious that various 40 modifications may be made without departing from the spirit of the invention; and it is to be understood that the apparatus itself may be susceptible to various adaptations other than the milling of wheat. All of such changes and adaptations are therefore contemplated as may come 45 within the scope of the claims.

What I claim is:

1. Scalping apparatus comprising a sieve box into which crushed kernels are introduced, means 50 for supporting said sieve box in an inclined position, said supporting means including a plurality of yielding members at each end of the sieve box acting at right angles to each other, each yielding member having a fixed axial position at 55 an angle to the plane of the sieve box, means for causing movement of the sieve box on said yielding members, and means for adjusting said yielding members to provide for movement of the sieve box in its entirety in an elliptical course wherein

the longer axis of said elliptical movement is at an angle to the plane of the sieve box to cause the crushed kernels to be bounced vertically on the sieves in such a manner as to minimize friction on said kernels.

2. Scalping apparatus comprising a sieve box into which crushed kernels are introduced, means for supporting said sieve box in an inclined position, said supporting means including a plurality of sets of opposed yielding members at each 10 end of the sieve box acting at right angles to each other, each yielding member having a fixed axial position at an angle to the plane of the sieve box, means for causing movement of the sieve box on said yielding members, and means for 15 adjusting said yielding members to provide for movement of the sieve box in its entirety in an elliptical course wherein the longer axis of said elliptical movement is at an angle to the plane of the sieve box to cause the crushed kernels to be bounced vertically on the sieves in such a manner as to minimize friction on said kernels.

3. Scalping apparatus comprising a sieve box into which crushed kernels are introduced, means for supporting said sieve box in an inclined position, said supporting means including a plurality of yielding members at each end of the sieve box acting at right angles to each other, each yielding member having a fixed axial position at an angle to the plane of the sieve box, 20 revolving eccentric weight means for causing movement of the sieve box on said yielding members, and means for adjusting said yielding members to provide for movement of the sieve box in its 25 entirety in an elliptical course wherein the longer axis of said elliptical movement is at an angle to the plane of the sieve box to cause the crushed kernels to be bounced vertically on the sieves in such a manner as to minimize friction on said 30 kernels.

4. Scalping apparatus comprising a sieve box into which crushed kernels are introduced, means for supporting said sieve box in an inclined position, said supporting means including a plurality of sets of opposed yielding members at each end 40 of the sieve box acting at right angles to each other, each yielding member having a fixed axial position at an angle to the plane of the sieve box, revolving eccentric weight means for causing movement of the sieve box on said yielding members, and means for adjusting said yielding members to provide for movement of the sieve box in its 45 entirety in an elliptical course wherein the longer axis of said elliptical movement is at an angle to the plane of the sieve box to cause the crushed kernels to be bounced vertically on the sieves in such a manner as to minimize friction on said 50 kernels.

LOUIS BURMEISTER.
